EXPANDABLE WATCHBAND

Pierre Luigi Casorati, Milan, Italy, assignor to Le Phare
S.A., La Chaux-de-Fonds, Switzerland

Filed June 3, 1968, Ser. No. 12,175

Claims priority, application Switzerland Feb. 12, 1968

Term of patent 14 years

U.S. Cl. D45—4
Int. Cl. D11—01

FIG. 1

FIG. 3

FIG. 1 is the top plan view of an expandable watchband in the normal relaxed state showing my new design;

FIG. 2 is the same view showing the watchband in an expanded state;

FIG. 3 is a side elevational view of the watchband in the expanded state.

I claim:

The ornamental design for an expandable watchband, substantially as shown.
